(57) **CLAIM**

The ornamental design for a notebook computer with camera bump, as shown and described.

DESCRIPTION

FIG. 1 is a top front perspective view of the notebook computer with camera bump according to the claimed design, with the notebook computer in a closed position; FIG. 2 is a top front perspective view of the notebook computer with camera bump according to the claimed design, with the notebook computer in an open position; FIG. 3 is a top rear perspective view of the notebook computer with camera bump according to the claimed design, with the notebook computer in the closed position; FIG. 4 is a top rear perspective view of the notebook computer with camera bump according to the claimed design, with the notebook computer in the open position; FIG. 5 is a front view of the notebook computer with camera bump according to the claimed design, with the notebook computer in the closed position;

FIG. 6 is a rear view of the notebook computer with camera bump according to the claimed design, with the notebook computer in the closed position;

FIG. 7 is a left side view of the notebook computer with camera bump according to the claimed design, with the notebook computer in the closed position;

FIG. 8 is a right side view of the notebook computer with camera bump according to the claimed design, with the notebook computer in the closed position;

FIG. 9 is a top view of the notebook computer with camera bump according to the claimed design, with the notebook computer in the closed position; and,

(Continued)

FIG. 10 is a bottom view of the notebook computer with camera bump according to the claimed design, with the notebook computer in the closed position.

The broken lines in the figures depict portions of the notebook computer with camera bump that form no part of the claimed design.

1 Claim, 6 Drawing Sheets
